UNITED STATES PATENT OFFICE.

LOUIS BELL, OF WEST NEWTON, MASSACHUSETTS, ASSIGNOR TO EDWARD N. GODING, TRUSTEE, OF NEWTON, MASSACHUSETTS.

DUAL SUPPLEMENTING HEADLIGHT.

Application filed February 13, 1920. Serial No. 358,536.

To all whom it may concern:

Be it known that I, LOUIS BELL, a citizen of the United States, residing at West Newton, county of Middlesex, Commonwealth of Massachusetts, have invented certain new and useful Improvements in Dual Supplementing Headlights, of which the following is a specification.

This invention relates to road illumination and particularly to the projection of a combined road illuminating beam from a motor vehicle or the like.

In this art much effort has been made to effect suitable distribution of light over the intercept of the beam of the roadway and at the same time to guard against offense in the upper portion of the beam to the eyes of pedestrians or approaching motorists. One of the requirements developed in this effort to secure suitable illumination has been lateral illumination adjacent the car and to the right thereof to guard against the rather frequent sudden appearance of a pedestrian from curb or other unexpected place not sufficiently illuminated by the ordinary light.

The object of my present invention is to cover all these several requirements and at the same time to increase the distance of illumination and the degree of illumination in that portion of the beam which constitutes the driving light. This has been variously attempted from different portions of the beam of each light.

In accordance with my invention I produce from the two conventional headlights of a vehicle by giving to each of them different optical characteristics, a combined beam of such unsymmetrical character as is desirable for the practical lighting of the roadway.

As illustrative of my invention I have shown certain forms of intercept as well as lens system for producing and combining such beams. This form I will discuss in the specification which follows, pointing out the adaptability of the features of it in the varying problems of road illumination. Throughout the specification and drawings like reference numerals are correspondingly employed, and in the drawings:

Fig. I is a diagrammatic view illustrating projection of the beam from a pair of unmodified headlights of normal construction.

Fig. II illustrates in corresponding dia-

gram a combined beam in accordance with my invention.

Figs. III and IV illustrate modified beams of similar character otherwise disposed.

Fig. V is a somewhat diagrammatic illustration of a pair of lenses shown in section with the beam distribution indicated.

Figs. VI and VII show a vertical section of the left hand and right hand lenses, respectively, of such pair.

Fig. VIII is a diagrammatic view showing a pair of conventional projectors in section.

In explanation of the drawings it may be said that in Fig. I the intersecting circles r, l indicate the projection of a pair of beams from a pair of ordinary automobile headlights unmodified. They consist, as will be seen, of two substantially circular and overlapping discs of equal intensity and of the same size. As before explained, it is the object of my invention to provide a combined beam in which distribution and intensity is varied.

For the purposes of the present application the lamps are referred to as right hand and left hand lamps, it being understood that this reference is made pursuant to the law of the road in this country which provides for keeping to the right.

In Fig. II I have illustrated such a combined beam in which r^1 is the right hand portion of the projection, and l^1 the left hand portion. This beam and other similar related beams may be projected from the incandescent bulbs b of a pair of projectors P, Fig. VIII, having right and left hand lenses R, L, respectively of the type, shown in my prior Patent No. 1,277,364, in which I employ cylindrical front and rear surfaces of crossed axes. The front surface L^1 is of vertical cylindricity, while the rear surface L^2 is of horizontal cylindricity. The same is true of the surface R^1 and R^2 of the right hand lens. In constructing this lens pair, however, the radius of the surface L^1 is greater than the radius of the surface R^1 of the right hand lens, while the radius of the surface L^2 of the left hand lens is less than that of R^2 of the right hand lens. Lenses so constructed may be designed to give a variety of intercepts of somewhat different combined characters. As shown in Fig. II, the left hand lens and

the right hand lens give some degree of depression, the former much less dispersion than the latter.

In this way, instead of the combined beam being symmetrically disposed about the vertical median plane M , M in the central axis of the system, the left hand lens L , looking in the direction of the beam, will produce a downwardly refracted beam with comparatively slight spread and relatively high intensity as appears at l^1 . The right hand lens R with greater lateral spread, while overlapping the first and adding somewhat to its intensity at O will serve to spread the beam widely over the right hand side of the roadway.

The right hand lens may be slightly toed out in addition to giving somewhat less deflection and greater lateral dispersion, so that its beam will only slightly overlap that of the left hand lens as shown in Fig. III, but extend considerably to the right with both greater dispersion and less depression than the left hand beam so as not only to give more light laterally, but also above and below the horizontal axis C , C of the lamp than would be desirable or permissible on the left hand side.

Such a combination gives instead of a combined beam of somewhat elliptical section, a beam approximately apioidal as indicated in dotted lines a , Fig. III, with the wider toward the right and the apex toward the left according to the different ratios of depression and dispersion in the two lenses.

The left hand lens may itself be slightly toed out so that the combined pair will give less light above the horizontal plane through the lamps in the center while preserving a comparatively condensed driving beam just to the left of the center overlapped by the more spreading illumination toward the right. Of course in regions where drivers turn to the left the arrangement of the lens would be reversed.

In Fig. IV, I have illustrated a further modification in which the left hand beam l^3 is held substantially as in Figs. II and III, the right hand beam is skived to give it an

upward and outward tilt. This is sometimes advisable where the left hand portion of the combined beam has to be held low and yet a higher lateral illumination is desired off to the right.

With the lenses herein shown as illustrative it is only necessary to incline the axis of the front cylindrical concavity R^1 slightly to the left or out of its right angled relation to the axis of R^2 .

What I therefore claim and desire to secure by Letters Patent is:

1. A pair of headlights each comprising a projector and each having a refractive screen spaced apart in the same plane, the screen of the left hand light having means to project a beam of substantially oval cross section and horizontal major axis and slight axial displacement, and the screen of the right hand headlight having means to project a beam of substantially oval cross section and horizontal major axis of greater length than that of the left hand headlight and overlapping the medial axis of said pair of screens, the upper end of the vertical axis of the left hand beam being substantially at the level of the lamp.

2. A pair of headlights each comprising a projector having a substantially parabolic reflector and each having a refractive screen, said headlights being spaced apart in the same plane, the screen of one headlight having means to project a beam of substantial oval cross section and of horizontal major axis of greater length than the other headlight and of less displacement with reference to its parabolic axis.

In testimony whereof I affix my signature in presence of two witnesses.

LOUIS BELL.
